UNITED STATES PATENT OFFICE.

FRANK H. CHASE, OF CHICAGO, ILLINOIS.

PENCIL-SHARPENER.

SPECIFICATION forming part of Letters Patent No. 761,944, dated June 7, 1904.

Application filed February 1, 1904. Serial No. 191,575. (No model.)

To all whom it may concern:

Be it known that I, FRANK H. CHASE, a citizen of the United States, residing at Chicago, in the county of Cook and State of Illinois, have invented certain new and useful Improvements in Pencil-Sharpener, of which the following is a specification.

This invention relates to pencil-sharpener of the kind which are adapted to be carried in a pocket, like those described in my applications Serial No. 162,307, filed June 20, 1903, and Serial No. 169,794, filed August 17, 1903.

The object of this invention is to provide a portable pencil-sharpener of simple construction which receives and confines the shavings within itself and is adapted to be folded into compact form with the cutting-blade protected when not in use.

Further objects of the invention are to simplify and improve the construction of the sharpener and reduce the cost of manufacture, to enable the sharpener to be readily opened or unfolded for use, and also to secure the knife-blade rigidly in place to provide for its easy removal for sharpening.

In the accompanying drawings, illustrating the preferred embodiment of the invention, Figure 1 is a perspective view of the sharpener closed. Fig. 2 is a plan view of the bottom or cutting side of the sharpener in open position. Fig. 3 is a longitudinal sectional view on the line 3 3 of Fig. 2. Fig. 4 is a top plan view of the sharpener opened, with the slip-lid also opened. Fig. 5 is a detail view of the knife-blade. Fig. 6 is a detail view of the locking-yoke. Fig. 7 is a transverse sectional view on the line 7 7 of Fig. 4. Fig. 8 is an end view looking at the right end of Fig. 3.

In the drawings like numerals of reference indicate corresponding parts in the several figures, and, referring thereto, 10 designates the casing, which is shown made of a single plate bent upon itself and its ends held together by the pivot-pin 11. This casing is cut out or recessed at 12 on its top and bottom near one end for a purpose hereinafter described. A frame 14 is pivotally secured on the pivot-pin within the ends of the casing,

and it is provided with a guard 15, which, with the knife-blade 16, forms the bottom of the 50 frame.

The knife-blade is adapted to be engaged at one end with the pivot-pin and held securely in place by a locking device which engages its other end. For this purpose the blade is provided at one end with a slot 17 to receive the pivot-pin, and at its other end with a projection 18 to enter an opening 19 in the downturned end 20 of a yoke 21, which fits within the casing, against the side walls thereof, with 55 its end 20 projecting through an opening 22 in the outer end of the casing. The locking-yoke is provided with a lug 23, which enters a slot 24 in the inwardly-turned flange 25 on the top of the casing, and when this lug rests 60 in said opening the yoke will be held against endwise movement and the downturned end 20 will be engaged with the blade to lock it securely in place. To unlock the blade, the lug 23 is disengaged from the opening 24 by 65 pressing it inward, and then pressure is applied to the lug to move the yoke lengthwise of the casing and disengage the end 20 from the blade, after which the blade can be swung back and withdrawn. When the blade is 70 again inserted in proper position, pressure is applied to the end 20 to move it into engagement with the blade, and the lug 23 again enters its opening 24 to lock the yoke and the blade in place. A guide 26 may be provided 75 for that end of the yoke which carries the lug 23. It will be observed that the yoke is shaped to fit within the casing, and its sides work against the sides of the casing and between its bottom and the inwardly-turned 80 flanges 25 25' at its top. The bodily movement of the yoke is limited in one direction by the outer end of the casing and by a downwardly-turned lug 27, so that it can never become displaced from the casing. 85

A slip-lid 28 forms a top for the frame and can be readily opened to permit the discharge of the shavings which have been collected in the frame, Fig. 4. A pin 28' on the casing projects into a slot 29 in the slip-lid and the 90 frame and limits the swinging movement of 95

the lid and frame, so that they will fit snugly within the casing when closed and aline properly with the casing when open for use.

This pencil-sharpener is compact in form and can therefore be conveniently carried in a pocket. It is adapted to be quickly opened for use and can be manipulated in the ordinary manner of sharpening a pencil with a penknife. By cutting out or recessing the casing in the manner illustrated it is made to form a handle which can be firmly held in the hand to facilitate the use of the device, and it also enables the frame to be readily grasped by the fingers to unfold or open the sharpener. The frame is entirely closed when the sharpener is in use except for the narrow slot which is of course provided between the knife and the guard, as shown in Fig. 7, to permit the knife to cut off a shaving from a pencil; but this slot is not of sufficient size to allow the shavings to escape from the frame. When the pencil has been sharpened, the slip-lid can be adjusted to the position shown in Fig. 4 and the shavings discharged. This slip-lid is provided with an opening 30 in its outer end to engage a stud 31 on the frame to prevent the lid from accidentally slipping to open position. The manner of securing and locking the blade in place is very simple and permits the blade to be readily and easily removed to be sharpened at any time.

Without limiting myself to the exact construction and arrangement of parts herein shown and described, what I claim, and desire to secure by Letters Patent, is—

1. A pencil-sharpener comprising a frame adapted to receive and confine the shavings, a knife-blade carried by said frame, and a casing constituting a handle for the sharpener

and formed of a single plate bent upon itself 40 and adapted to infold the frame, said casing being pivotally connected at the ends of the plate to the frame and recessed or cut out on the corresponding edge of its top and bottom and near the outer end thereof.

2. A pencil-sharpener comprising a folding casing and frame, a knife-blade carried by and removable from the frame, and a device for locking the blade to the frame.

3. A pencil-sharpener comprising a folding 50 casing and frame, a pin pivotally connecting the casing and frame, a knife-blade provided with a slot to receive said pivot, and a device for locking said blade to the frame.

4. A pencil-sharpener comprising a frame, 55 a knife-blade carried by and removable from the frame, and a locking device operating within the frame and having a part projecting through the frame to engage and secure the blade to the frame.

5. A pencil-sharpener comprising a frame, a knife-blade carried by said frame, a yoke 60 slideable in the frame, and a lug on the yoke extending through an opening in the frame and adapted to make locking engagement with the blade.

6. A pencil-sharpener comprising a frame, a knife-blade carried by said frame, a yoke within the frame, a lug on the yoke projecting through an end of the frame to make locking engagement with the blade, and a lug on the yoke within the frame to make locking engagement therewith.

FRANK H. CHASE.
